UNITED STATES PATENT OFFICE.

JOHN M. COLLINS, OF SOUTH PITTSBURG, TENNESSEE.

RAILROAD CONSTRUCTION.

No. 839,781.

Specification of Letters Patent.

Patented Dec. 25, 1906.

Application filed April 27, 1906. Serial No. 314,072.

To all whom it may concern:

Be it known that I, JOHN M. COLLINS, a citizen of the United States, residing at South Pittsburg, in the county of Marion and State of Tennessee, have invented certain new and useful Improvements in Railroad Constructions, of which the following is a specification.

This invention embodies improvements in the construction of railroads, and relates to that type of inventions in which a hollow metallic tie is utilized, together with peculiar means for securing the rails to the tie, a filler of concrete, asphalt, cement, or similar plastic material being used to fill the hollow bodies of the metallic ties.

The essential feature of the invention resides in the peculiar construction of the detail parts included therein and other features the advantages of which will appear more fully hereinafter.

The invention also includes a construction of attaching means between rails and ties wherein the metallic tie is dispensed with and the wooden tie is used in connection with parts hereinbefore mentioned.

For a full understanding of the invention and the merits thereof and also to acquire a knowledge of the details of construction of the means for effecting the result reference is to be had to the following description and accompanying drawings, in which—

Figure 1 is a transverse sectional view through a road-bed, ties being shown constructed in accordance with the invention, as well as the means for securing the rails thereto. Fig. 2 is a section taken on the line X X of Fig. 1. Fig. 3 is a detail perspective view of one of the angle-bars used to secure the rails to the tie. Fig. 4 is a vertical section showing the adaptation of the invention when wooden ties are used in construction of the road-bed. Fig. 5 is a detail view of one of the angle-bars employed at a joint between two rails, the said bar being formed with square bolt-receiving openings.

Corresponding and like parts are referred to in the following description and indicated in all the views of the drawings by the same reference characters.

In the drawings the numeral 1 designates a hollow metallic tie, preferably made of heavy sheet or cast metal and formed with a longitudinal slot 2 in its bottom portion. The ties when of hollow form are preferably of somewhat rectangular contour in cross-

section with the corner portions rounded, as shown most clearly in Fig. 2. Adjacent to each end of each tie are spaced vertical openings 3, formed in the top portions thereof, so as to receive hooks 4, projecting from the lower portions of angle-bars 5, provided to support the rails 6 at opposite sides, said angle-bars being connected by the usual bolts or fastenings 7 and being prevented from displacement from the tie by the interlocking connection established between the hooks thereof, which project downwardly therefrom and beneath the top of the tie. To subserve the rigidity of the ties and the perfect ballast of the road-bed, it is contemplated that the said ties when in position shall be filled with a filler 8, of cement, asphalt, or concrete, which is placed in the ties when in plastic state and permitted to harden in an obvious manner. The filler 8 also cooperates to prevent looseness or play of the means whereby the angle-bars 5 are connected with the ties and in this capacity are of great advantage.

In the modification shown in Fig. 4 the wooden tie 9 is utilized and is provided adjacent to its ends with spaced recesses or seats 10, into which the hooks 4 of the angle-bars 5 are received. In this construction a bed-plate 11 is securely attached by spikes or similar fastenings to the upper side of the tie 9, near an end thereof, and this bed-plate is formed with openings 12, just above the recesses 10, so that the hooks 4 of the angle-bars may project through such openings 12 and enter the recesses 10 when the interlocking connection of the angle-bars is established.

At intermediate points along the rails the angle-bars are comparatively short and are preferably each provided with two bolt-openings, as indicated in Fig. 3, while at the joints between the rails longer angle-bars 5 are employed which are provided with four bolt-openings, two for each rail, as shown in Fig. 5. Attention is also directed to the fact that the bolt-receiving openings in the angle-bars 5 on the inside of the track have a square or angular formation and engage in the usual manner with the heads of the bolts to prevent them from turning while the nuts are being placed in position.

It will be noted that in the construction shown in Figs. 1 and 2 the cement filling the hollow metallic tie constitutes a ballasting-body, the top of the metallic tie comprising a

plate secured to the ballasting-body in an evident manner. Similarly the wooden tie in the construction in Fig. 4 constitutes a ballasting-body to the upper side of which a top plate is secured. In both constructions the rail is secured to the plates at the top of the ballasting-body, the hooks of the angle-bars being countersunk in the manner specified.

Having thus described the invention, what is claimed as new is—

Means of the class described, consisting of a tie composed of a ballasting-body, a top plate applied to the ballasting-body and formed with spaced openings, rails having the base portions thereof resting on the top plate, angle-bars at opposite sides of the rails

and having hooks projecting from the lower portions thereof and passing through the openings of the top plates and countersunk in the ballasting-body of the tie, said hooks 20 engaging beneath the top plate to prevent displacement of the rails therefrom, and fastenings passing through the angle-bars and the rails and connecting said angle-bars in the manner specified. 25

In testimony whereof I affix my signature in presence of two witnesses.

JOHN M. COLLINS. [L.S.]
